UNITED STATES PATENT OFFICE.

FRANK DUNHAM, OF NEW YORK, N. Y.

CLOTHES-DRYER.

1,018,037.

Specification of Letters Patent. Patented Feb. 20, 1912.

Application filed October 11, 1910. Serial No. 586,489.

To all whom it may concern:

Be it known that I, FRANK DUNHAM, a citizen of the United States, and a resident of New York, county and State of New York, have invented certain new and useful Improvements in Clothes-Driers, of which the following is a full, clear, and exact specification.

This invention relates to a class of devices or driers adapted for use in conjunction with hot water boilers, steam pipes and radiators by which the heat therefrom may be utilized for drying clothes, or the like.

My invention has for its object primarily to provide a form of drier of simple, inexpensive and efficient construction which may be readily applied to hot water boilers, steam pipes and radiators for supporting clothes, towels, and various articles of household, linens after being washed and which is adapted to receive and transmit sufficient heat therefrom for utilization in drying the wet articles, and this is accomplished by providing one or a plurality of tubular devices or brackets having a substantially U-shaped body and a supporting arm which is adapted to be removably held to said boilers, steam pipes or radiators.

A further object of the invention is to provide efficient means adapted to permit the tubular devices to be conveniently attached or detached from the boilers, pipes or radiators and which will allow a desired number of said devices to be simultaneously employed.

A practical embodiment of the invention is represented in the accompanying drawing forming a part of this specification in which similar characters of reference indicate corresponding parts in all the views, the said invention being more fully described hereinafter and then pointed out in the appended claims.

In the drawing, Figure 1 is an elevation of a hot water boiler with my improved clothes drier applied thereto. Fig. 2 is an elevation of a steam pipe showing the manner of using the clothes drier in conjunction therewith. Fig. 3 is an elevation of the device as applied to a radiator. Fig. 4 is a top plan of a radiator showing the means for connecting the pipe thereto. Fig. 5 is a top plan of a strip or band formed of two members for attaching the drying devices to a boiler or pipe, and Fig. 6 is a top

plan of the fastening strip or band when integrally formed.

In practice my clothes drier 10 may be made in the desired sizes so as to be applied to any hot water boiler, or steam or hot air pipe, as 11^a of any diameter. The drier 10 consists mainly of a tubular device or bracket 12 and one or a plurality of strips or bands or supporting elements 13. The strips or bands 13 may be made of sheet metal or heavy wire, the ends of which are bent outwardly to form a flange, as 14 and 15, and in both of said flanges is provided an opening through which is passed a thumb screw 16 for firmly tightening the bands 13 when directed around a hot water boiler or steam pipe. Each of the strips or bands or supporting elements 13 may be formed of a single piece of material or comprise two strips or members 17 and 18, each having an apertured flange upon the ends thereof which may be also connected by similar thumb screws. The strips 13 or members thereof are corrugated or provided at intervals with extending curved parts 20 so as to form a plurality of spaces 21 between said curved parts and the boiler or pipe when the strips are positioned thereon.

Through corresponding spaces 21 of each of the strips 13 is guided the tubular vertically disposed supporting rod 22 of the device or bracket 12 when it is desired to use one or more of said devices for drying purposes. Upon one end of the tubular supporting rod 22 and disposed at a right angle thereto is provided one arm 23 of a substantially U-shaped tubular body 24 which is formed by curving a tube so as to provide a second arm 25 in spaced parallel relation from the arm 23, thus the device may be substantially rectangular in form. The second arm 25 of the U-shaped tubular body 24 is provided with a number of perforations or openings 26 for passage therethrough of the heat which is received by the device 12 from a hot water boiler or heated pipe and driven toward said perforations by the current of air passing through the open end of the tubular supporting rod 22 to and through the U-shaped tubular body 24 and out through the opening at the end of the second arm 25 thereof.

When the device 12 is used in conjunction with a radiator for utilizing the heat therefrom to dry clothes, or other articles I em-

ploy a pipe or tubular rod 26 Fig. 3 to which said device is attached in the same manner as when connected to a standing steam or hot water pipe. The tubular rod or support 5 26, as indicated in the drawing, is preferably positioned adjacent to and between the coils of the radiator and through said tubular rod is formed an opening through which is guided the pin 27 of a clamp 28. Upon one 10 end of the pin 27 is a thumb screw 29 and upon the opposite end thereof is provided a head or flange 30 which is adapted to engage one or more of the coils of the radiator opposite to the side against which the tubular rod 28 rests. The pin 27 is thereby directed between two of the coils of the radiator so that said tubular rod will be firmly held to the radiator in an upright position by simply tightening the thumb screw 29. 15 20 In the foregoing description I have embodied the preferred form of my invention, but I do not wish to be understood as limiting myself thereto, as I am aware that modifications may be made therein without departing from the principle or sacrificing any 25 of the advantages of this invention, therefore I reserve to myself the right to make such changes as fairly fall within the scope thereof. 30 Having thus described my invention, I claim as new and desire to secure by Letters Patent:—

1. In a clothes drier of the character described, a device consisting of a tube which

is bent in a substantially rectangular form 35 and having its lower horizontal portion provided with a plurality of perforations. 40 2. In a clothes drier of the character described, the combination with a suitable support, of a substantially rectangular tubular device having its lower horizontal portion provided with a plurality of perforations, and means adapted to detachably connect one of its vertical end portions to such suitable support. 45 3. In a clothes drier of the character described, a supporting pipe, a device consisting of a tube which is bent in a substantially rectangular form and having a perforated lower horizontal portion, and means adapted 50 to detachably connect one of the vertical end portions to the supporting pipe. 4. In a clothes drier of the character described, the combination with a suitable support, of a corrugated band removably held 55 to the support, and a substantially rectangular tube having one of its vertical portions guided through one of the corrugations of the band and having a plurality of perforations provided in its lower horizontal portion. 60

This specification signed and witnessed this eighth day of October A. D. 1910.

FRANK DUNHAM.
